UNITED STATES PATENT OFFICE

2,462,091

COLLAPSIBLE STOCK FOR FIREARMS

John C. Garand, Springfield, Mass., assignor to
the United States of America as represented by
the Secretary of War

Application June 3, 1946, Serial No. 674,005

3 Claims. (Cl. 42—72)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to improvements in collapsible stocks for firearms with special reference to firearms of military type.

Modern warfare requires that firearms be as light in weight as possible and also occupy a minimum of space. Weapons of this type are particularly necessary to airborne troops. Some form of stock is essential for the accurate firing of such firearms, yet the conventional stock does not meet the necessary limited weight and space requirements. To this end, there have been developed some rifle and gun constructions having so-called collapsible or folding stocks. However, the constructions heretofore known have not been sufficiently rigid when locked in the extended position to withstand constant use of the firearm. Such requirement is especially vital in the case where grenades are to be fired from such firearms as are provided with folding stocks. Exceptionally large recoil forces are encountered in discharging grenades from conventional firearms and such forces tend to exert considerable stress and strain on the folding stock and particularly at the junction point of the firearm and folding stock.

Moreover it is an added requirement that folding stocks be firmly and positively locked in the firing position yet be quickly and easily changed to either the firing or the collapsed position. The locking means should also be simple in operation and readily accessible to the operator of the firearm.

Furthermore in launching grenades from firearms, it is particularly desirable to employ a special sight for obtaining the necessary accuracy. One form of such sight consists of pivotally mounting a sighting bar on a circular base, such base being fixedly secured to the stock of the firearm. It can readily be seen that known collapsible stocks for a firearm would prevent the use of the sight here mentioned. However, one of the improvements of this invention over prior art resides in the fact that the collapsible stock is so designed that it may carry a circular mounting base for a grenade sight.

Accordingly it is an object of this invention to provide improved locking means for a collapsible stock.

A further object of this invention is to provide means for mounting a circular base for a grenade launching sight to such firearm as is provided

2

with a collapsible stock whereby a sight mounted on such base does not interfere with the proper stowing of the stock in a folded position.

A particular object of this invention is to provide locking means for a collapsible stock which will present a rigid and shock-resisting construction when such stock is in the firing position, especially where excessive recoil forces are encountered, as in the launching of grenades.

10 The specific nature of the invention as well as other objects and advantages thereof will clearly appear from a description of a preferred embodiment as shown in the accompanying drawings in which:

15 Fig. 1 is a side-elevational view of the collapsible stock assembled to a firearm and shown in the extended position;

Fig. 2 is a side-elevational view of a portion of Fig. 1 showing the opposite side of the ferrule construction;

20 Fig. 3 is a side elevational view of the collapsible stock in the folded position;

Fig. 4 is a cross-sectional view showing how the ferrule fits on the stock forearm;

25 Fig. 5 is a perspective view of the collapsible stock member;

Fig. 6 is a top plan view of the locking mechanism for the collapsible stock shown partly in cross section;

30 Fig. 7 is a cross-sectional view taken along lines 7—7 of Fig. 6; and

Fig. 8 is a plan view of the latch member of the invention.

In Fig. 1 a collapsible metal stock 2 is shown in assembled relation to a wooden forearm 3 commonly associated with a firearm of the type known as U. S. rifle, cal. .30, M1. Forearm 3 is of conventional construction and is provided with openings toward the rear for accommodating a receiver 4 and a trigger guard 5 indicated in Fig. 1 by dot-dash lines. Arcuate cuts 6 are provided near the front end of forearm 3 for receiving portions of collapsible stock 2 when such is in a folded position as shown in Fig. 3.

45 A metal sleeve member or ferrule 7 is fitted to the rear end of forearm 3 and provides mounting facilities for folding stock 2. Ferrule 7 is substantially U-shaped and channeled so as to conform to the outer periphery of forearm 3 and fits snugly thereon when assembled. The top of ferrule 7 is bent inwardly as shown at 8 in Fig. 4 to provide a flat surface against which receiver 4 abuts when assembled to the firearm. The bottom of ferrule 7 is bent inwardly and upwardly as shown at 9 in Fig. 4 to assure the required snug

fit thereof to forearm 3. A conventional pistol grip 10 extends downwardly from the forearm-fitting portion of ferrule 7 and may be removably attached or integral therewith. On each side of ferrule 7 there is provided a longitudinal slot 11. An arcuate slot 12 is provided on the right side as shown in Fig. 1 for a purpose to be explained.

The collapsible stock 2 includes an upper support member 13 and two lower supporting arms 14 and 14'. Carried between member 13 and arms 14 and 14' is a butt plate 15 preferably perforated as shown at 16 in Fig. 5 and shaped to accommodate the shoulder of the user of the firearm. Upper support member 13 is preferably a U-shaped rod passing through the inwardly turned sides of butt plate 15 and extending forwardly thereafter to form parallel arms 17. The lower supporting arms 14 and 14' consist of a pair of parallel spaced-apart flat bars riveted to butt plate 15 at 18 and capable of pivoting movement thereon. Oppositely opposed detents 19 are provided on the inner surface of each arm 17 for a purpose to be shown.

The forward ends 20 of arms 17 are flattened out and apertured to receive a bolt 21 therethrough so that upper support member 13 can be pivotally mounted to ferrule 7. Lower supporting arms 14 and 14' terminate in end sections 22 curving upwardly and rearwardly so as to form projections in the shape of hooks 23. Such hooks 23 are for camming purposes as will later be shown. End sections 22 are apertured to receive screws 25 by means of which arms 14 and 14' are also pivotally mounted to ferrule 7. Screws 25 are provided with a stepped-down head and shoulder 26 whereby such screws protrude sufficiently from the sides of ferrule 7 to insure non-binding and free-pivotal movement of arms 14 and 14'. Suitable slots are provided on the interior faces of the receiver opening of forearm 3 to receive rectangular nuts 27 and 27' which act to provide bearing surfaces for tightening ferrule 7 to forearm 3. Nut 27 is also provided with a tongue 28 which acts in a manner to be described. Arm 14' is provided with an extension 29 at the end of which a graduated grenade sight mounting base 30 is riveted or otherwise attached.

A rotatable latch member 31 illustrated in Fig. 8 for locking collapsible stock 2 in an extended position consists of a body 32 and a lever arm 33 extending at right angles therefrom. Lever arm 33 is provided with a lug 34 adapted to engage arcuate slot 12 so as to limit the movement of latch 31 in either direction. Camming cuts 35 are provided in opposite ends of body 32 to cooperate with hooks 23 as will be explained. A circumferential groove 36 is provided in body 32 near the lever-arm end thereof for engagement with the aforementioned tongue 28 to prevent any lateral movement of latch 31. A lightening cut 37 is preferably also provided in body 32 for reducing the weight of latch member 31.

A helical torsion spring 38 is wound about body 32 and a free end thereof is inserted in a longitudinal locating groove 39 in body 32 while the other free end extends sufficiently to abut bolt 21 as shown in Fig. 6. Spring 38 is slightly pre-loaded and acts to maintain lever arm 33 at the end of arcuate slot 12 farthest from the rear of ferrule 7.

To collapse stock 2 from the extended position shown in Fig. 1, lever arm 33 is retracted sufficiently to disengage from beneath hooks 23. Latch 31 will, of course, return to its original posi-

tion under the bias of latch spring 38. Then by pivoting stock 2 downwardly and forwardly until stopped by forearm 3, it will assume the collapsed position shown in Fig. 3 with the lower edges of butt plate 15 entering arcuate cuts 6 on the underside of forearm 3. At the same time detents 19 will engage longitudinal slots 11 whereby collapsible stock 2 will be prevented from accidental displacement from the folded position due to jarring.

To open collapsible stock 2 from the folded position to the fully extended position shown in Fig. 1, such stock is first pulled away from the forearm 3 so that detents 19 disengage from slots 11 in ferrule 7. Then stock 2 is pivoted in a reverse manner to that necessary for collapsing. Hooks 23 will enter camming cuts 35 and strike lever arm 33 and cam such rearwardly. The upward pivoting movement of collapsible stock 2 will be terminated by arms 14 and 14' abutting upper parallel arms 17. As a result, hooks 23 clear camming cuts 35 and since latch 31 is rotated to its original position under the urging of latch spring 38, a portion of lever arm 33 will engage beneath hooks 23 to positively lock collapsible stock 2 in an extended or firing position. The contact of arms 14 and 14' against forward ends 20 of arms 17 provides extra rigidity of the collapsible stock in its extended or firing position.

Moreover, stock 2 when locked in an extended position has ample rigidity and strength to withstand the extra strain and stress encountered as a result of the forces developed by launching grenades from the firearm.

A fixed sight base 30 may be secured to the forward end of arm 14' by any suitable means for mounting a grenade-launching sight (not shown) thereon. Such base does not interfere with collapsing the stock.

I claim:

1. In a firearm having a collapsible stock constructed to be locked in an extended position and a wooden forearm, a metallic ferrule rigidly secured to the rear end of the forearm by a bolt and screws extending transversely therethrough, one of said screws threaded into a locking nut having a projecting tongue thereon, a rotatable latch transversely disposed in said ferrule and the forearm, said latch having a circumferential groove for engagement with said tongue to prevent lateral displacement of said latch, a spring surrounding said latch and having one free end thereof disposed within a longitudinal slot in said latch and the other free end abutting said bolt, a cam ear on each end of said latch providing means for mechanically locking the stock when the stock is moved into the extended position and a lever-like member on one end of said latch above said cam ear for manually unlocking the stock therefrom.

2. In a firearm having a wooden forearm and a collapsible shoulder stock having a pair of long and short parallel arms straddling the forearm and pivotally mounted thereto, means pivotally interconnecting the outer portions of said long and short arms, said mounting providing for movement of the stock from a collapsed to an extended position, a metallic ferrule rigidly secured to the rear end of the forearm, said ferrule having a slot on each side thereof, a detent on the inner face of each short parallel arm adapted to engage said slot when the stock is swung to the collapsed position, a rotatable latch inserted through said ferrule and the forearm, and means

on the pivoted ends of the long parallel arms for receiving the ends of said latch therein when the collapsible stock is swung to the extended position relative to the forearm, all constructed and arranged whereby the stock in the collapsed position is prevented from accidental displacement and whereby the stock in the extended position is positively locked.

3. In a firearm having a forearm and a collapsible shoulder stock including a pair of long and short parallel arms straddling the forearm and pivotally mounted thereto providing movement of the stock from a collapsed to an extended position and coacting means on each short parallel arm and the forearm to releasably retain the stock in the collapsed position, a hook-like camming projection on the pivoted end of each long parallel arm, a ferrule secured to the rear end of the forearm, said ferrule having an arcuate slot disposed on one side thereof, a rotatable latch transversely mounted in said ferrule, said latch being provided with a cam ear on each end thereof, a lever-like member on one end of said latch above one of said ears, an inwardly facing lug on said lever adapted to engage said arcuate slot, and resilient means biasing said latch for-

wardly, all adapted and arranged whereby said hook-like camming projections are cammed past said ears rotating said latch rearwardly when the collapsible stock is swung from the collapsed to the extended portion and whereby said latch returns to the original position under the bias of said resilient means rotating said ears beneath said hook-like camming projections to positively lock the collapsible stock in an extended position relative to the forearm.
